HENRY E. VAN NESS, OF ELMIRA, NEW YORK

DYEING APPARATUS

Original application filed March 11, 1926, Serial No. 93,821. Divided and this application filed October 27, 1926. Serial No. 144,412.

This invention relates to dyeing apparatus and more particularly to apparatus for carrying out the method of dyeing one or more predetermined parts of an absorbent mass, which is described and claimed in Patent No. 1,724,015, issued to Eclipse Textile Devices, Inc., on August 13, 1929. The present application is a division of my co-pending application filed March 11, 1926, Serial No. 93,821.

The object of the apparatus with which the present application is concerned is to facilitate carrying out the method of dyeing in which the dyeing liquid is passed rapidly through a predetermined limited part of a wound mass of yarn, coloring this part of the yarn only; and more particularly to aid in carrying out a specific method of spot-dyeing yarn wound in the form customarily known as a cross-wound cone of yarn. This specific method, which is described and claimed in my aforesaid co-pending application, is as follows:—

A cone of yarn is positioned with the axis of its core vertical and with the larger open end of its core pointing upward. The cone is rotated rapidly, for example, at a speed of 2000 R. P. M. about the axis of its core. During the rotation, liquid is supplied to limited zones of the inner surface of the mass of yarn, that is, the surface adjacent to the core.

The liquid used is a dyeing solution in which the coloring matter is suspended, or, more desirably dissolved, in water or other relatively non-volatile liquid (as distinguished from a volatile liquid, such as alcohol, which evaporates quickly). The dyeing solution is preferably hot and may include about 20% of an assistant, such as Turkey red oil, or other chemical to assist the coloring matter in penetrating the pores of the yarn.

The solution is poured into the upper, open end of the core before or during the rotation, reaches parts of the inner surface of the mass through perforations previously provided in two spaced zones of the core, is forced by centrifugal force into and through the zones of the mass of yarn which lie radially outward from the two perforated zones of the core, and is then thrown off from the outer surfaces

of these zones before it can soak into or color the portions of the mass between and outside these two zones. The supply of the solution to the inner surface of the zones is continued until the passage of the solution through the zones has colored them to the desired tint. The supply of liquid to the inner surfaces of the zones is then stopped, and the rotation is continued until no further liquid or mist is thrown off from the outer surfaces of the zones. This results in leaving the two zones, which have been dyed, substantially dry, and thus eliminates all danger of subsequent coloring of other parts of the mass by liquid soaking into them from the dyed zones.

The method described may be modified to produce a single colored zone, or any desired number of separated colored zones, by perforating a single zone, or the desired number of separate zones, of the core of the mass.

A convenient form of apparatus, embodying the present invention, and adapted to aid in carrying out the method described is illustrated in the accompanying drawings in which:—

Fig. 1 is an elevation in axial section; and

Fig. 2 is a fragmentary axial section showing a modified deflector which may be used in the apparatus shown in Fig. 1.

The apparatus illustrated includes a vertical shaft 10 supported on spaced bearings 11. The shaft may be rapidly rotated by means of a power-driven belt 12 passing over a pulley 13 fixed on the shaft, or by other convenient means. A foraminous frusto-conical holder 15 is secured to the upper end of the shaft 10. The holder 15 is enclosed by a fixed casing 16 having at its lower end an opening 17 for the passage of the shaft and at its upper end a large opening 18 registering with the large open end of the holder 15 to permit placing of a cone of yarn C in the holder. The casing is provided with a valve-controlled drain pipe 19 and with a flange 20 surrounding its lower opening 17 to prevent liquid from reaching the bearings of the shaft 10.

The core C¹ of the cone C is provided at two spaced zones with closely spaced perforations C², C³. Liquid may be introduced into the core C¹ from pipe 25, extended through

the opening 18 in the casing 16 into the large open end of the core C¹. This pipe is mounted so that it may be moved to permit the removal of the cone C and the insertion of a new cone.

5 A deflector 26 is provided to prevent the liquid in the hollow core C¹ from splashing over the upper end surface of the cone C. The deflector has a conical portion 27 fitting into the large end of the core and an upstanding lip 28.

10 The carrying out of the method already described by means of this apparatus will result in dyeing two spaced zones C⁴, C⁵ of the mass which lie radially outward from the sets of perforations C², C³, leaving the remainder of the mass uncolored.

15 The modified deflector 26', shown in Fig. 2, may be substituted for the deflector 26. The lower portion 27' of this deflector forms a conical cup fitting against the entire inner surface of the core of the mass, so that the deflector is held very firmly within the core. The cup 27' of the deflector is provided with 20 two series of openings 30, 31, which register with the perforations C², C³ of the core C¹ when the deflector 26' is inserted in this core. The deflector 26' may, however, be used with a core C¹ which is perforated throughout, 25 since the two sets of openings 30, 31 of the deflector limit the supply of the liquid to the inner surface of the mass to two spaced zones.

30 What I claim is:—

1. Apparatus for dyeing a cone of yarn, comprising a hollow conical perforated core on which the yarn is wound, means for rotating the yarn and core with the open end of the core upward, means for supplying liquid to the interior of the core through its open end, and means for preventing said liquid from splashing out of the open end of the core during the rotation.

2. Dyeing apparatus, comprising the combination with means for rotating a cone of 40 yarn wound on a perforated core and means for supplying liquid to the interior of said core, of a conical cup fitting into the core, containing lateral perforations, and having a lip extending outward from the open end 45 of the core.

3. Apparatus for spot-coloring yarn on the cone by means of centrifugal force, comprising a conical cage rotatably mounted with its larger end uppermost and open to receive 50 a cone of yarn and to confine the outer surface thereof, means for applying a coloring liquid to a limited portion of the interior surface of the cone of yarn in the cage, and means for rotating the cage with the cone 55 therein at a rate of speed sufficient to cause the coloring matter to pass radially through the cone from its point of application, leaving the remainder of the cone uncolored.

4. In an apparatus for spot-coloring yarn 60 wound in cone formation, a conical cage for

frictionally engaging the periphery of the yarn cone, means for rotating the cage with the cone therein, a hollow conical mandrel frictionally engaged with the interior surface of the yarn cone for receiving rotary motion therefrom, and means for introducing a coloring fluid into the mandrel, said mandrel having restricted passages communicating with the interior of the yarn cone for permitting the flow of the coloring fluid to and through the yarn by centrifugal force as the yarn cone is rotated.

5. In an apparatus for spot-coloring yarn wound in hollow mass formation, a cage rotatable about a vertical axis and open at the top and provided with perforated peripheral walls for frictional engagement with the outer periphery of the yarn mass, a rotary mandrel coaxial with and projecting into the upper end of the cage for frictionally engaging the interior of the yarn mass, said mandrel being provided with means for applying coloring liquid to limited portions of the interior area of said mass, and means for rotating the cage and mass therein together with the mandrel at a rate of speed sufficient to cause the coloring liquid to pass from the interior to the periphery of the mass of yarn.

6. Apparatus for spot-coloring yarn wound in hollow mass formation, comprising means for introducing a coloring liquid into the interior of the mass into contact with a limited zone of the inner surface thereof, means for rotating the mass at a rate of speed sufficient to cause the coloring liquid to pass from the interior through and to the exterior of the portion of the mass lying radially outward from the zone to which the coloring matter is applied, and foraminous means confining the outer surface of the mass during such rotation to prevent disruption of the mass.

70 In testimony whereof I have hereunto set my hand.

HENRY E. VAN NESS.
